AUTOMOBILE DOOR HANDLE

Masaji B. Sugano, Detroit, Mich., assignor to General Motors Corporation, Detroit, Mich., a corporation of Delaware

Application September 23, 1953, Serial No. 26,918

Term of patent 7 years

(Cl. D10—8)

To all whom it may concern:

Be it known that I, Masaji B. Sugano, a citizen of the United States and a resident of Detroit, Wayne County, Michigan, have invented a new, original, and ornamental Design for an Automobile Door Handle, of which the following is a specification, reference being had to the accompanying drawing, forming a part hereof.

Fig. 1 is a front elevational view of an automobile door handle showing my new design;

Fig. 2 is a perspective view thereof;

Fig. 3 is an end elevational view;

Fig. 4 is a sectional view taken on the plane indicated by the line 4—4 in Fig. 1;

Fig. 5 is a sectional view taken on the plane indicated by the line 5—5 in Fig. 1; and

Fig. 6 is a sectional view taken on the plane indicated by the line 6—6 in Fig. 1.

I claim:

The ornamental design for an automobile door handle, substantially as shown.
